TEMPERATURE-CONTROLLING DEVICE FOR INTERNAL-COMBUSTION ENGINES

Application filed October 30, 1924. Serial No. 746,896.

The invention relates to a temperature controlling device for regulating the temperature of the fuel mixture delivered to an internal combustion engine.

5 Due to high efficiency that it is necessary to obtain in internal combustion engines at the present time, it is necessary to use high compression. Due to using this high compression, it is necessary to have a very sensitive 10 temperature control on the carbureting device used in connection with the same. The carbureted gas temperature desirable under ordinary working conditions is about 150° F. However, under extreme conditions 15 countered in commercial work, it is desirable to have the carbureted gas temperature as low as possible in the carbureting device due to the fact that the carbureted mixture will pick up the necessary heat in passing 20 through the valve chambers and cylinder head due to overheating of the cooling system. It is also desirable in a carbureting system to have the arrangement of heat application so that the atomized fuel will receive 25 the heat from the exhaust gas immediately the engine has started and that the heating chamber of the carbureting system be not allowed to drop too much in temperature during the first starting of the engine when 30 cold, which would allow raw fuel to be drawn over into the cylinders causing dilution of the lubricant. This carbureting temperature control device consists of a carbureting chamber surrounded with a hot gas chamber, the 35 hot gas being received from the exhaust manifold and the amount of hot gas controlled by a thermostat which can be set to give the desired temperature in this chamber. Manual means are also arranged so that the entire 40 exhaust gas can be put through this hot gas chamber or the hot gas can be shut off entirely from this chamber to cover extreme conditions such as extreme cold or hot weather 45 conditions.

With these and other objects in view the invention consists in the construction and novel combination and arrangement of parts hereinafter fully described, illustrated in the accompanying drawings and pointed out in 50 the claims hereto appended, it being under-

stood that various changes in the form, proportion and minor details of construction, within the scope of the claims, may be resorted to without departing from the spirit or sacrificing any of the advantages of the 55 invention.

In the drawings:

Figure 1 is a side elevation of a temperature controlling device constructed in accordance with this invention and shown applied to an internal combustion engine. 60

Figure 2 is an enlarged longitudinal sectional view of the temperature controlling device. 65

Figure 3 is a plan view of the device. 65

Figure 4 is a horizontal sectional view through the hot gas chamber. 65

Figure 5 is a horizontal sectional view through the thermostat receiving section, illustrating the arrangement of the valve. 70

Figure 6 is a detailed sectional view of the exhaust pipe, illustrating the arrangement of the outer casing of the intervening insulation. 70

In the accompanying drawings in which is illustrated the preferred embodiment of the invention, 1 designates an intake pipe connecting the carburetor 2 of an internal combustion engine 3 with the intake manifold 4 thereof. The intake pipe is provided preferably at a point immediately above the carburetor 2 with a thin walled section 5 arranged within and surrounded by a hot gas chamber 6, and preferably constructed of copper or some other suitable material of high seat conductivity. The hot air chamber 6 is formed by an outer shell or casing 7 surrounding the thin walled section and connected at its upper portion at one side with a branch 8 of an exhaust pipe 9a. The branch 8 of the exhaust pipe may be connected with the casing 7 at any other desired point and the said casing is enlarged at one side at the upper portion at 10 to receive the branch pipe 8. The said casing is also preferably enlarged at the opposite side at the lower portion at 11 to afford a convenient connection for a discharge pipe 12 for conducting the exhaust gases from the hot gas chamber surrounding the inlet pipe. 10

The exhaust pipe 9a and the exhaust manifold 13, are insulated to prevent heat from radiating from the exhaust manifold and the exhaust pipe with its branch 8, and affecting the temperature conditions of the internal combustion engine. This will render the temperature controlling device more sensitive and will increase the range of operation of the temperature controlling device. 5
10 In other words, the inlet pipe may be supplied with a maximum amount of heat from the exhaust pipe or the heat from the exhaust pipe may be entirely cut off from the inlet pipe or any intermediate condition may be 15 maintained from such extremes. The insulation of the exhaust manifold and the exhaust pipe and its branch 8, may be effected by any suitable means such as by providing an outer casing 14 of aluminum or other 20 suitable material and a filling, packing or the like. For convenience of illustration, also for efficiency, a corrugated insulation member 15 is shown for providing an intervening air space between the outer casing 25 and the exhaust manifold and exhaust pipe. The branch pipe 8 is equipped with a manually operated valve 9 for controlling the passage of the exhaust gases through the branch pipe 8 from the exhaust pipe 9a to the hot 30 gas chamber 6, and the exhaust pipe may also be provided with any suitable means beyond the juncture of the same with the branch 8 such as a valve 10a for enabling all 35 of the exhaust gases from the engine to be passed through the hot gas chamber when necessary or desirable. By this construction a complete control and elimination of the exhaust gases from the hot gas chamber and inlet pipe to a passage of all of the gases of 40 the exhaust of the engine through the hot gas chamber may be obtained. Any suitable means may be provided for operating the valve 9, which is shown of the pivoted butterfly type, but any other desired construction 45 may of course be employed.

The exhaust gases passing through the hot gas chamber and impinging against and heating the inlet pipe 5 are automatically controlled by means of a thermostat 16 located within a section 17 of the discharge pipe 12 and connected with and actuating a valve 18, which cooperates with a valve seat 19 at the upper end of the discharge pipe 12. The valve 18 controls the outlet opening 20 in the lower enlargement 11 of the outer shell or casing 7. The thermostat is mounted on a lug 21 projecting interiorly from the section 17 of the discharge pipe and receiving a stem 22 of the thermostat. The stem 22 is threaded for a nut 23 which secures the stem in the opening 24 of the lug 21, but it will be apparent that the thermostat may be mounted in any other desired manner. The upper end of the thermostat is provided with 65 a stem 25 suitably secured to the valve 18,

which operates in a suitable guide and support 26 located at the upper end of the section 17 of the discharge pipe 12, but the valve may be constructed and mounted in any other preferred manner. The thermostat while being arranged in the path of the exhaust gases discharging from the hot gas chamber is located exteriorly of the hot gas chamber and may be constructed of material commercially practical owing to the location of the thermostat in a relatively cool portion within the discharge pipe and thereby avoiding the high temperatures to which the thermostat would be necessarily subjected if located within the hot gas chamber. The thermostat may be set for various temperatures as will be readily understood and when it is desired to maintain the aforesaid 150° F. of the inlet pipe, the thermostat will be set for approximately 160° F. and will close the valve 18 and prevent the passage of exhaust gases through the discharge pipe and through the hot gas chamber when the temperature exceeds that degree. The valve 18 is purely automatic in its operation and is independent in its operation of the valve 9 of the branch 8 of the exhaust pipe, the valve 9 being designed particularly for use in the extreme conditions heretofore pointed out. Also by locating the thermostat within the discharge pipe, it is not only out of the way, but it entirely eliminates the trouble and inconvenience of locating such an element exteriorly of the pipe in which the valve actuated by its is arranged.

While a valve may be employed in the exhaust pipe beyond the branch pipe for positively causing all of the exhaust gases to pass through the hot air chamber under ordinary conditions, the resistance offered by the muffler with which the exhaust pipe will be equipped will be ample to cause the desired flow of the exhaust gases through the branch pipe and the hot air chamber.

What is claimed is:

1. A temperature controlling device including an inlet pipe located between the carburetor and the engine and forming a passage for the fuel mixture, a hot gas chamber surrounding the inlet pipe and having at one side an upper inlet and at the other side a lower outlet, means for conducting exhaust gases from the engine to the inlet of the said chamber, said chamber permitting the gases to circulate entirely around the inlet pipe and discharged at the said outlet, and means exterior to the said chamber and located beyond the outlet thereof in the direct path of and regulated by the discharging exhaust gases after the same have passed through the outlet of the hot gas chamber and have left the latter for controlling the passage of the exhaust gases from the hot gas chamber and the temperature of the intake pipe.

2. A temperature controlling device including an inlet pipe located between the carburetor and the engine, a hot gas chamber surrounding the inlet pipe and provided at one side at the upper portion with an inlet and at the opposite side at the lower portion with an outlet, an exhaust pipe having a branch connected with the inlet of the hot gas chamber for delivering exhaust gases to the same for heating the inlet pipe, and means exterior to the hot gas chamber and located beyond the outlet in the direct path of and regulated by the discharging gases after the same have passed through the outlet of the hot gas chamber and have left the latter for controlling the discharge of exhaust gases from the hot gas chamber and the temperature of the intake pipe.

3. A temperature controlling device for internal combustion engines including an inlet pipe located between the carburetor and the engine, a jacket surrounding the inlet pipe and carrying a section of the same and provided at the upper portion at one side with an inlet and at the opposite side at the lower portion with an outlet, said jacket forming a hot gas chamber and permitting the hot gases to circulate entirely around the inlet pipe, an exhaust pipe having a branch connected with the inlet of the jacket for delivering exhaust gases to said chamber for heating the inlet pipe, and means exterior to the jacket and located beyond the outlet thereof in the direct path of and regulated by the discharging gases after the same have passed through the outlet of the hot gas chamber and have left the latter for controlling the passage of exhaust gases from the hot gas chamber and the temperature of the inlet pipe.

4. A temperature controlling device for internal combustion engines including an outlet pipe located between the carburetor and the engine, a jacket surrounding the inlet pipe and forming a hot gas receiving chamber and provided at the upper portion at one side with an inlet and at the opposite side at the lower portion with an outlet and permitting the hot gases to circulate entirely around the inlet pipe, an exhaust pipe having a branch connected with the said jacket for delivering exhaust gases to the said chamber for heating the inlet pipe, means exterior to the said jacket and located beyond the said outlet in the direct path of and regulated by the discharging gases after the same have passed through the outlet of the hot gas chamber and have left the latter for controlling the passage of the exhaust gases from the hot gas chamber and the temperature of the inlet pipe, and a manually operable valve arranged within said branch for controlling the passage of the hot gases to the casing in extreme conditions and capable of also closing the branch pipe to the exhaust gases.

5. A temperature controlling device including an inlet pipe located between the carburetor and the engine, a hot gas chamber surrounding the inlet pipe and provided at the upper portion at one side with an inlet and at the opposite side at the lower portion with an outlet, an exhaust pipe having a branch connected with the inlet of the hot gas chamber for delivering exhaust gases to the same for heating the inlet pipe, a valve located exteriorly of the outlet and beyond the same and cooperating with the same, and thermostatically actuated means located exteriorly of the hot gas chamber and beyond the valve in the direct path of and regulated by the discharged exhaust gases after the same have passed through the outlet of the hot gas chamber and have left the latter for operating the valve to control the passage of the exhaust gases through the said outlet and the temperature of the inlet pipe.

6. A temperature controlling device for internal combustion engines including an inlet pipe located between the carburetor and the engine, a hot gas chamber surrounding the inlet pipe and provided at one side with an inlet and at the opposite side with an outlet adapted to cause the hot gases to entirely envelope the inlet pipe, an exhaust pipe insulated from the engine to prevent radiation of heat from the exhaust pipe to any part of the engine, said exhaust pipe having means for connecting it with the inlet of the said chamber, means for cutting off the exhaust gases entirely from the hot gas chamber when required, and automatic means arranged exteriorly of the hot gas chamber and located beyond the said outlet in the direct path of and regulated by the exhaust gases discharging from said chamber after the said gases have passed through the outlet of the chamber and left the latter for controlling the passage of the exhaust gases through the outlet and the temperature of the inlet pipe.

7. A temperature controlling device for internal combustion engines including a thin walled inlet pipe, a hot gas chamber surrounding the inlet pipe and having relatively thick walls and provided at one side with an inlet and at the opposite side with an outlet, means for introducing hot exhaust gases into said chamber for heating the inlet pipe and for controlling the passage of said gases to the chamber so that in extreme conditions all of the exhaust gases may be delivered to the hot gas chamber or excluded therefrom, and automatic means located exteriorly of the hot gas chamber beyond the said outlet in the direct path of and regulated by the exhaust gases discharging therefrom after said gases have left the said chamber through the said outlet for controlling the passage of the said gases through the outlet and the temperature of the inlet pipe.

8. A temperature controlling device for in-

- ternal combustion engines including an inlet pipe located between the carburetor and the engine, a hot gas chamber surrounding the inlet pipe and provided at the upper portion 5 at one side with an inlet and having a lateral enlargement at the bottom at the opposite side provided with an outlet, a discharge pipe leading from the outlet of the said enlargement, a valve located in the discharge pipe 10 exteriorly of the enlargement, and a thermostat also located in the discharge pipe exterior of the said chamber and the enlargement thereof and arranged in the direct path of the exhaust gases passing from the said chamber, said thermostat being connected with and actuating the valve for controlling the passage of the exhaust gases through the outlet and the temperature of the inlet pipe.
9. A temperature controlling device for internal combustion engines including an inlet pipe located between the carburetor and engine, a hot gas chamber surrounding the inlet pipe and provided at the upper portion at one side with an inlet and at the opposite side 15 at the bottom with an enlargement having a bottom outlet, an exhaust pipe having a bracket connected with the inlet of the hot gas chamber and provided with a valve for controlling the passage of all of the exhaust gases to cause the same or any amount thereof to pass to the hot gas chamber and to exclude all of the exhaust gases therefrom when required, a discharge pipe depending from the said enlargement of the hot gas chamber 20 at the bottom outlet thereof, a valve located exteriorly of the enlargement and operating in the discharge pipe, and a thermostat also located exteriorly of the enlargement and arranged in the discharge pipe in the direct path of the exhaust gases, said thermostat being connected with and actuating the valve of the discharge pipe for controlling the passage of the exhaust gases through the outlet and the temperature of the inlet pipe.
- 45 10. A temperature controlling device for internal combustion engines including an inlet pipe located between the carburetor and the engine, a hot gas chamber surrounding the inlet pipe and carrying a section thereof and provided at one side at the upper portion with an inlet and at the opposite side at the bottom with a lateral enlargement having a bottom outlet, an exhaust pipe having a bracket connected with the inlet of the hot 50 gas chamber and provided with a valve for controlling the passage of the exhaust gases to the chamber, a discharge pipe depending from the enlargement and surrounding the outlet thereof and provided with an upper guiding portion and having a lower supporting lug, a valve cooperating with the outlet and operating in the guiding portion of the discharge pipe, and a thermostat mounted upon the said lug and connected with the valve and 55 60 65 70 75 80 85 90 95 100 105 110 115 120 125 130
- adapted to actuate the same for controlling the passage of the exhaust gases through the outlet, said valve and thermostat being located exteriorly of the hot gas chamber and the thermostat being in the direct path of the exhaust gases discharging from the chamber.
- In testimony whereof I have hereunto set my hand.
